UNITED STATES PATENT OFFICE.

MILTON S. DUNKELBERGER, OF DAYTON, OHIO.

DESIGN FOR A COLLAPSIBLE BABY-CARRIAGE.

57,773.

Specification for Design.

Patented May 3, 1921.

Application filed October 4, 1920. Serial No. 414,679. Term of patent 14 years.

To all whom it may concern:

Be it known that I, MILTON S. DUNKELBERGER, a citizen of the United States, residing at Dayton, in the county of Montgomery and State of Ohio, have invented a new, original, and ornamental Design for a Collapsible Baby-Carriage, of which the following is a specification, reference being had to the accompanying drawing, forming part hereof.

Figure 1 is a side view, in perspective,

and Fig. 2 is a rear view, in perspective, of a collapsible baby-carriage, showing my new design.

I claim:

The ornamental design for a collapsible baby-carriage, as shown.

MILTON S. DUNKELBERGER.

Witnesses:

HOWARD S. SMITH,
WILLIAM B. HORMELL.
